FIG. 2

FIG. 1 is a perspective view taken from the top and one end of a cigarette lighter showing my novel design, seen from one end of the lighter;

FIG. 2 is a bottom plan view of the lighter shown in FIG. 1; and

FIG. 3 is an elevational view showing that end of the lighter which is not seen in FIG. 1.

The appearance of the side of the cigarette lighter not shown in the drawing is identical with the appearance of the side shown in FIG. 1.

I claim:

The ornamental design for a cigarette lighter, substantially as shown and described.
